UNITED STATES PATENT OFFICE

95,548

DESIGN FOR A CHARACTER DOLL OR SIMILAR ARTICLE

Edward J. Rogers, Kansas City, Mo.

Application March 9, 1935, Serial No. 55,798

Term of patent 14 years

To all whom it may concern:

Be it known that I, Edward J. Rogers, a citizen of the United States, residing at Kansas City, in the county of Jackson and State of Missouri, have invented a new, original, and ornamental Design for Character Doll or Similar Article, of which the following is a specification, reference being had to the accompanying drawing, forming part thereof.

Fig. 1 is a front elevational view of a character doll or similar article showing my new design.

Fig. 2 is a side view of the doll or similar article showing my new design.

I claim:

The ornamental design for a character doll or similar article, as shown.

EDWARD J. ROGERS.
